Patented Dec. 4, 1923.

1,476,240

UNITED STATES PATENT OFFICE.

LOUIS C. EDWARDS, OF ELLINGTON, CONNECTICUT.

TOBACCO-STRIPPING TABLE.

Application filed March 6, 1922. Serial No. 541,445.

To all whom it may concern:

Be it known that I, LOUIS C. EDWARDS, a citizen of the United States, residing at Ellington, in the county of Tolland and State 5 of Connecticut, have invented certain new and useful Improvements in Tobacco-Stripping Tables; and I do declare the following to be a full, clear, and exact description of the invention, such as will enable others 10 skilled in the art to which it appertains to make and use the same.

This invention relates to an improved tobacco stripping table and one object of the invention is to provide a table so constructed 15 that tobacco carrying laths may be placed upon the table in a vertical plane and the laths moved longitudinally so that the tobacco leaves carried thereby will be brought into engagement with supports for the laths 20 and thus caused to be moved out of engagement with the laths and be left free so that a tray upon which the leaves rest may be moved away from the laths and supporting means for the laths to a position where the 25 leaves can be easily gathered and formed into a hand.

Another object of the invention is to so construct this stripping table that a lath can be easily and quickly put in place by an 30 operator and the means for imparting movement to the laths then moved to impart the desired movement a second operator then moving the tray to the position permitting the second operator to readily gather the 35 leaves and form them into the hand.

Another object of the invention is to so construct this table that when the lath is put in place, it will be positioned between arms which are pivotally connected with the 40 table and extend beyond the edge thereof and have their outer ends connected by a handle bar so that the two arms may be simultaneously moved and impart longitudinal movement to the laths, first in one direction 45 and then in the other.

Another object of the invention is to so construct this table that the leaf carrying tray may be guided in its sliding movement and prevented from moving out of the 50 proper relation to the lath and carrying means.

This invention is illustrated in the accompanying drawings, wherein:

Figure 1 is a view showing the table principally in top plan, the lath and lath-holding

means being shown in section and leaves being shown resting upon the leaf tray and engaged with the laths.

Figure 2 is a view showing the upper portion of the table in front elevation. 60

Figure 3 is a top plan view of the table with the laths in place and the leaf-holding tray removed.

Figure 4 is a view similar to Fig. 1 showing the laths moved to disconnect certain of 65 the tobacco leaves from the lath.

Figure 5 is a transverse sectional view taken along the line 5—5 of Fig. 1.

Figure 6 is a longitudinal sectional view taken along the line 6—6 of Fig. 1. 70

This tobacco stripping outfit includes a table 1 which is of a conventional construction and carries guiding strips 2 which extend transversely of the table upon the upper face thereof and have their inner side 75 faces undercut as shown in Fig. 6 so that the guide strips 2 may extend in overlapping relation to the cleats 3 secured to the underface of the leaf-carrying tray 4 and thus guide sliding movement of the tray 80 and serve to prevent movement of the tray longitudinally of the table and also serve to prevent the tray from being lifted off of the table when in use.

In order to support the leaf-carrying lath 85 5 in a vertical position, there has been provided supporting strips 6 and 7 which are secured to the table upon opposite sides of a strip 8 which extends between the guide strips 2. The supporting strips 6 are secured against the forward side face of the table as shown in Fig. 2 and the strips 7 have their lower ends bent to provide seats 7' which will be secured upon the upper face 90 of the table with the strips positioned in recesses formed in the strip 8 as shown in Fig. 3. The upper ends of these strips 6 and 7 which will be formed of resilient metal are flared as shown in Figs. 3 and 5 so that the laths can be easily put in place. 100

When the lath is put in place, the operator stands in front of the table and swings the lath away from him over the table and then draws it towards him and thrusts it downwardly between the strips 6 and 7. In this position, the tobacco leaves will rest upon the tray as shown in Fig. 1 with their butt ends extending through the lath and between the sets of strips 6 and 7. After the lath has been put in place, it is 110

necessary to move the lath longitudinally first in one direction as shown in Fig. 4 and then in an opposite direction. When the lath is moved longitudinally, the butt ends 5 of the tobacco leaves will be brought into engagement with the lath-supporting strips and as the lath continues its sliding movement, the leaves will be moved out of engagement with the prongs 5' of the lath. 10 In order to impart the desired sliding movement to the lath, there has been provided arms 9 which are pivotally connected with the table and extend beyond the forward edge of the table at points which will place 15 the arms beyond the ends of the laths as shown in Fig. 1. A hand-bar 10 connects the outer ends of these arms so that they may be simultaneously swung upon their pivot points and straps 11 are provided to 20 limit swinging movement of the arms. From an inspection of Fig. 4, it will be readily seen that when the handle-bar 10 is moved in one direction, the laths will be engaged by one of the arms 9 and moved to 25 bring certain of the tobacco leaves into engagement with the supporting strips 6 and 7 and move them out of engagement with the prongs. It will also be obvious that when the handle-bar is moved in the opposite direction, the remaining tobacco leaves which are in engagement with prongs of 30 the lath will be moved out of engagement with these prongs. After the lath has been moved first in one direction and then in the 35 other to disconnect the leaves from the prongs of the lath, the operator who sits at the opposite side of the table will draw the tray away from the lath. The tray will carry with it the leaves and when the leaves 40 have been drawn out of a position in which they will extend through the lath, the operator can pick them by the butt ends and form them into a hand. The tray can then be returned to the original position and the 45 arms 9 and handle bar 10 returned to the position shown in Fig. 1 so that another lath carrying tobacco leaves can be easily put in place. It will thus be seen that with this improved tobacco stripping table, the 50 laths can be easily and quickly put in place and given the desired movement to remove the tobacco leaves from engagement with the laths and the tobacco leaves then formed into the hand.

I claim:

1. A tobacco stripping outfit comprising a table, supporting means carried by said table for mounting a tobacco lath for longitudinal sliding movement, means for imparting sliding movement to a lath held by the supporting means and bringing leaves carried by the lath into engagement with the supporting means to move the leaves out of engagement with the lath. 55

2. A tobacco stripping outfit comprising a table, supporting means carried by said table for mounting a tobacco lath for longitudinal sliding movement, means for imparting sliding movement to a lath held by the supporting means and bringing leaves carried by the lath into engagement with the supporting means to move the leaves out of engagement with the lath, and a leaf holding tray carried by said table and movable toward and away from the supporting 60 means transversely of a lath supported thereby. 70

3. The structure of claim 1 having the lath supporting means consisting of a plurality of strips extending upwardly from the table at spaced points across the table for extending upon opposite sides of the lath to slidably support the lath in a vertical plane and guide the laths when moved. 80

4. The structure of claim 1 having the means for moving the lath longitudinally consisting of arms pivotally connected with the table and extending for engagement with the ends of the lath, and a hand bar connected with the arms for imparting 85 swinging movement to the arms and moving the lath longitudinally. 90

5. The structure of claim 2 having the table provided with guide strips, the tray being provided with cleats engaging the 95 guide strips to permit sliding movement of the tray transversely of the table towards and away from a lath supported by the lath supporting means and hold the tray against movement longitudinally of the table. 100

6. A tobacco stripping outfit comprising a table, and common means for mounting a lath for reciprocating movement across the table and removing leaves from the lath during reciprocation thereof. 105

In testimony whereof I have hereunto set my hand.

LOUIS C. EDWARDS.
